US00D510929S

(12) **United States Design Patent** (10) Patent No.: **US D510,929 S**
 Laverick et al. (45) Date of Patent: **** Oct. 25, 2005**

(54) **ANTENNA FOR COMBINED PERSONAL DIGITAL ASSISTANT AND NAVIGATION DEVICE**

(75) Inventors: **David Laverick**, Overland Park, KS (US); **Christopher Hanshew**, Lenexa, KS (US); **Brian G. Schoenfish**, Kansas City, KS (US); **David Lammers-Meis**, Prairie Village, KS (US)

(73) Assignee: **Garmin Ltd. (KN)**

(**) Term: **14 Years**

(21) Appl. No.: **29/200,548**

(22) Filed: **Mar. 1, 2004**

Related U.S. Application Data

(63) Continuation of application No. 29/181,088, filed on May 5, 2003, now Pat. No. Des. 484,127.

(57) **CLAIM**

The ornamental design for an antenna for combined personal digital assistant and navigation device, as shown and described.

DESCRIPTION

FIG. 1 is a perspective view of an antenna showing our new design;

FIG. 2 is a rear elevation view of the antenna;

FIG. 3 is a front elevation view of the antenna;

FIG. 4 is a first side elevation view of the antenna;

FIG. 5 is a second side elevation view of the antenna;

FIG. 6 is a top plan view of the antenna; and,

FIG. 7 is a bottom plan view of the antenna.
